UNITED STATES PATENT OFFICE.

GUILLERMO FREUND, OF LIMA, PERU.

PNEUMATIC ACTION FOR PLAYER PIANOS.

Application filed March 12, 1923. Serial No. 624,616.

To all whom it may concern:

Be it known that I, GUILLERMO FREUND, citizen of Peru, residing at Lima, Peru, have invented certain new and useful Improvements in Pneumatic Actions for Player Pianos, of which the following is a specification.

The present invention relates to pneumatic actions for player pianos; and it provides certain improvements, notably in the construction of the action chest, and of the valve action, all as hereinafter fully described.

As is generally known, it has heretofore been customary to construct the action chest of a pneumatic action of wood—usually in the form of a bar or block which is recessed and perforated to produce the exhaust chamber and the various passages and ports communicating therewith; and it has also been usual to construct the valve boxes of wood and separately from the action chest, and then to detachably or otherwise connect the boxes and chest together, the boxes being likewise bored or recessed to form the necessary chambers, passages and ports. Such procedure is, of course, expensive; and as the wood is apt to swell and shrink under changing atmospheric and temperature conditions, loose joints frequently result and, on occasions, more or less permanent distortion. According to my invention, however, the use of wood is discarded, and the chest is constructed entirely of metal, preferably in the form of two separate main parts which are soldered together; one part constituting the base or bottom of the chest, and the other part the front, rear and top walls. Sheet brass may advantageously be utilized for the construction of both main parts, as well as for the two end walls of the chest, the second or body part being machine-shaped.

The striker pneumatics are connected to the base of the chest, as usual; but the valve boxes, which contain the devices for controlling these pneumatics, are disposed within the chest and fastened to the base thereof, instead of being arranged in front of the chest, and they are likewise constructed of sheet brass, instead of wood, as heretofore. The valve devices themselves are simplified, and improved means are provided for mounting them and for effecting

their connection with the tubes leading from the ducts of the tracker.

The accompanying drawings illustrate, by way of example, one form which the invention may take in practice; and therein:

Figure 1 is a transverse vertical section of the action;

Fig. 2 is a horizontal section on line 2—2, Fig. 1;

Fig. 3 is an end view of the chest;

Fig. 4 is a perspective view of one of the valves.

Referring more particularly to the drawings, the improved action chest, as shown, comprises two main parts 1 and 2, constructed of sheet brass; the body part 1 being bent or shaped by suitable machinery to form the front and rear walls 1¹ and 1² and the sloping top wall 1³, while the base part 2 is merely a flat plate, the two parts being soldered together. The end walls 1⁴ are likewise made of sheet brass and supported upon the base 2, and are soldered thereto and to the edges of the walls 1¹ and 1² to form an airtight structure, the interior of which is adapted to be connected with the usual vacuum-producing mechanism (not shown) through the intermediary of the pipe 15 that opens through the bottom of the chest.

In the front wall 1¹ of the chest there is formed a series of openings, corresponding in number to the ducts in the tracker; and in each of these openings there is soldered an internally-threaded sleeve 3 which is disposed with its longitudinal axis horizontal. Each sleeve 3 has an internal circumferential flange 3¹ at its inner end, against which is clamped, by the action of an externally-threaded inner sleeve 5, a metal disk 4 formed on its front face with a centering boss 4¹ and having a strip 4² of cork or other fibrous material secured to its rear face. A metal tube is soldered in an eccentric opening in disk 4 and projects beyond the same at opposite ends, its front portion 13 extending through and beyond the inner clamping sleeve 5 and providing a support to which is connected the adjacent end of the tube 16 leading from the corresponding duct in the tracker (not shown).

The rear portion 14 of the metal tube extends into the action chest and is provided adjacent its end with an opening 14¹, and

beyond this opening with a plug 17 having a bleed 18 therethrough. The opening 14¹ is formed in the under side of the tube in line with an opening 7¹ formed in the upper wall 5 of a collapsible diaphragm or pouch 7 whose opposite walls have fibrous disks 6 and 6² secured to them; the upper disk 6 being also secured to the under side of the tube portion 14 and having a central opening 6¹ which 10 registers with the openings 14¹ and 7¹, so that communication is thus provided between the tracker duct and the interior of the diaphragm. As a vacuum normally exists in the action chest, and as the tracker 15 ducts are normally closed to atmospheric air excepting when the perforations in the note sheet are brought into registration therewith, it will be apparent that the diaphragm or pouch will be normally collapsed, due to 20 its communication with the interior of the chest through the bleed 18. But when the tracker duct is uncovered by a note sheet perforation, then air will pass through the duct and the tracker tube 16 into and 25 through the metal tube 13—14, and thence through the registering openings 14¹, 6¹, 7¹ into the diaphragm 7, which will be expanded thereby.

The expansion or inflation of the various 30 diaphragms is utilized for the purpose of operating the striker pneumatics 12, of which there is one individual to each tracker duct, as usual. The pneumatics have their upper 35 members fixed to the base of the action chest, and their movable lower members provided with suitable devices 19 for operative connection with the key actions, so that when any pneumatic is collapsed, the movement of its lower member will actuate the corresponding key in the usual way. The operation 40 of the pneumatics for this purpose is controlled by the valve mechanisms herein-after described, which mechanisms, in turn, are controlled by the movements of the diaphragms or pouches 7.

According to the invention, each such mechanism or device comprises a box or casing 8 disposed transversely within the action chest and fastened to the bottom wall 50 or base 2 thereof, and having a somewhat elliptical shape. The bottom wall of this box—which, of course, is formed by the chest bottom or base 2—is provided with two openings; and in the rear opening is fitted the upper end of a metal throat or nipple 11 which projects downwardly into the interior of the pneumatic 12 through an opening in the upper wall thereof. The front opening receives an upstanding annular metal cap 10 which is also secured to the chest bottom; a backing strip 20 of cork or other fibrous material being fastened to the lower face of said bottom to render the joints as tight as possible, and the upper 60 member of the pneumatic being cut away 65

on its upper face, as indicated at 21, to provide communication, through the aforesaid cap, between the interior of the box and the atmosphere.

In the top of the valve box, directly opposite the cap 10, there is formed an opening 22 which is also located directly below and in line with the disk 6² on the diaphragm 7. These two openings—i. e., the opening 22 and the upper end of the cap 10—are alternately opened and closed by the lower or body portion 9¹ of the valve 9, which portion is faced at top and bottom with suitable yielding material such as rubber or leather, as shown. The stem portion 9² of the valve projects upwardly through the opening 22 and is of irregular cross-section, for instance stellate or cruciform, so as to enable the passage of air through said opening while, at the same time, preventing appreciable lateral movement of the valve. In consequence of this construction, the suction created in the action chest by the operation of the pedals will be free to act on the valve, which is thereby raised, its body portion 9¹ thus closing opening 22 and shutting off communication between the interior of the chest and the interior of the valve box. The latter, however, is in communication with the atmosphere through the aforesaid opening 22, so that the striker pneumatic will likewise communicate with the atmosphere through the nipple 11 and, hence, will be in expanded condition.

When a perforation in the note-sheet is brought opposite the corresponding duct in the tracker, and air is admitted to the associated diaphragm or pouch 7, then the expansion of the latter will cause its disk 6² to press down the valve, whereby the opening 22 is uncovered and the cap 10 is closed; the result being that the vacuum in the chest is free to act, through the valve box and the nipple 11, on the pneumatic, which is thereby collapsed and operates the key-action. When the note-sheet perforation passes beyond the duct, conditions are again reversed and the various parts restored to their normal positions.

It will be understood from the foregoing that the inner or clamping sleeves 5 can be readily unscrewed individually from their respective outer sleeves 3, thus releasing the corresponding disks 4 which can thereupon be withdrawn from the action chest through the said sleeves 3, carrying with them the metal tubes 13—14 and the diaphragms or pouches 7. The tracker tubes 16, which are usually flexible, can, of course, be readily detached from the front parts 13 of the metal tubes before the latter are withdrawn from the chest. Hence, in the event of any of the above-mentioned parts becoming displaced or injured, it can easily be adjusted or replaced by a new part, ac-

cording as may be necessary. The construction of the chest and valve boxes of metal, rather than of wood, greatly prolongs their effective life and avoids danger of accident 5 dental injury or distortion, as previously explained.

I claim as my invention:—

1. In a pneumatic action for player pianos and the like, an all-metal action chest embodying a flat base plate forming the 10 bottom of the chest, a sheet bent to form the front and rear walls and the top, and plates forming the end walls, all of said parts being rigidly connected together; and a series of 15 all-metal valve boxes disposed within the chest and mounted on the bottom wall thereof.

2. In a pneumatic action for player pianos and the like, an all-metal action chest; and 20 a series of all-metal valve boxes disposed within the chest and mounted on the bottom wall thereof.

3. In a pneumatic action for player pianos and the like, the combination of an action 25 chest; a valve box within the chest mounted on the bottom wall thereof and having alining openings in its top and bottom walls which communicate, respectively, with the interior of said chest and with the atmosphere; a striker pneumatic secured to said 30 chest and constantly communicating with the interior of the valve box; a single valve in said box to control both openings and thereby govern communication between the 35 interiors of the box and chest; and a tracker-controlled diaphragm for operating said valve.

4. In a pneumatic action for player pianos and the like, the combination of an action 40 chest; a valve box within the chest mounted on the bottom wall thereof and having alining openings in its top and bottom walls; a striker pneumatic secured to said chest and constantly communicating with the interior 45 of the valve box; a valve in said box to control said openings and thereby govern communication between the interiors of the box and chest, said valve having a stem which projects through the opening in the top wall 50 of the box; a fixed tube mounted in the front wall of the chest and adapted for connection at its front end with a tracker tube; and a collapsible and expandible pouch connected to the rear end of the fixed tube immediately 55 above the valve stem to operate the valve consequent upon its expansion.

5. A pneumatic action according to claim 4, in which the fixed tube is provided at its rear end with a plug having a bleed, and is 60 also provided in advance of said plug with an opening registering with a central opening in a disk secured to the upper face of the pouch, said central opening registering with an opening in said pouch face; and in

which a second disk is secured to the lower 65 face of the pouch to directly engage and depress the valve stem.

6. In a pneumatic action for player pianos and the like, the combination of an all-metal action chest having a series of internally-threaded sleeves fixed in and opening through its front wall; an externally-threaded clamping sleeve removably engaged in each fixed sleeve; a valve mechanism mounted in said chest in line with each 70 pair of sleeves; and a tracker-controlled valve-actuating device individual to each valve mechanism removably mounted in each fixed sleeve and clamped in place therein by the corresponding removable sleeve. 75

7. In a pneumatic action for player pianos and the like, the combination of an all-metal action chest having a series of internally-threaded sleeves fixed in and opening through its front wall, each sleeve having an inner circumferential flange; a disk disposed within each sleeve against the flange thereof; an externally-threaded sleeve removably engaged in each fixed sleeve to clamp the corresponding disk in place therein; a valve 80 mechanism mounted in said chest in line with each pair of sleeves; and a tracker-controlled valve-actuating device secured to each disk and removable bodily with the 85 same. 90

8. In a pneumatic action for player pianos and the like, the combination of an action chest; a valve box having alining openings in its top and bottom walls which lead directly into the action chest and to the atmosphere, respectively; a striker pneumatic secured to said chest and constantly communicating with the interior of the valve box; a single valve in said box to control both 100 openings and thereby govern communication between the interiors of the box and chest; and a tracker-controlled diaphragm for operating said valve. 105

9. In a pneumatic action for player pianos and the like, the combination of an action chest; a valve box having alining openings in its top and bottom walls which lead directly into the action chest and to the atmosphere, respectively; a striker pneumatic secured to said chest and constantly communicating with the interior of the valve box; a single valve in said box to control both 110 openings and thereby govern communication between the interiors of the box and chest; a fixed tube mounted in one wall of the chest and adapted for connection at its outer end with a tracker tube; and a collapsible and expandible pouch connected to the inner end of the fixed tube and disposed between 115 said tube end and the valve to operate the latter consequent upon its expansion. 120

GUILLEMMO FREUND.
